STERILIZER APPARATUS

Martin C. Schwab, Chicago, Ill.

Application September 15, 1933, Serial No. 689,521

3 Claims. (Cl. 128—214)

My invention relates to a positive sterilizer in combination with apparatus for giving intravenous or subcutaneous injections and the like.

Heretofore in the art it has been customary in one form in giving injections in hospitals, or other places, to take a certified ampule of concentrated glucose, or the like, prepared in an outside laboratory, and break off the glass top. This, of course, involves the danger of exposure to the contamination of the air and also the danger of minute particles of the glass falling into the glucose and passing on to the patient causing reactions and serious complications. Heretofore this glucose from the ampule or from any other supply has been poured into a container and diluted with distilled water or the like as required. The desired mixture is then poured into a fountain container which again involves exposing the liquid to possibilities of contamination, and foreign bodies which may be in the air or the containers. The liquid is then passed through a tubing, air being supplied indirectly to the container from the atmosphere, again exposing the glucose to contamination as above described.

Among the objects of my invention are to eliminate the rehandling of glucose, or the like, so as to prevent the possibility of contamination and the introduction of minute foreign matter. To prevent a secondary exposure of the glucose after it is once placed in a sealed container and to, therefore, provide a container from which the glucose is passed directly to the system of a patient without rehandling and danger of contamination. My invention eliminates secondary steps and apparatus with their usual exposure to the introduction of foreign matter and bacteria. With my invention I provide sterile air free from all organic and substantially all inorganic matter to allow liquid to flow out of a container and if a vacuum is present to break the vacuum in the container, said sterilization being accomplished by heating means. I further provide through my invention a certified solution and means for providing the same to the user. Another object is to provide a sterilizer which in one form becomes also a connecting member between the fountain container and the tubing which supplies sterile air to break the vacuum in the fountain container, and such other objects, advantages and capabilities as will later more fully appear and which are inherently possessed by my invention.

While I have suggested herein preferred embodiments of my invention yet I wish it under-

stood that the same are susceptible of modification and change without departing from the spirit of my invention.

Referring more particularly to the drawings, Fig. 1 is a side elevational view of one embodiment of my invention; Figs. 2 and 3 are side elevational views of a portion of other embodiments of my invention; Fig. 4 is another view of the embodiment shown in Fig. 1; Fig. 5 is a view of another type of heating means as applied to my invention; Fig. 6 is a detailed view of my improved container; Fig. 7 is a detailed view of an air cooler attachment.

In the embodiment selected to illustrate my invention in Fig. 1 I provide a connecting member 10 which can be immediately substituted for the sealed cap of the fountain container or bottle 11. My connecting member 10 has means for sealing itself to the fountain container, such as screw threads 12 which engage screw threads 13 on the bottle 11. Said connecting member 10 has at its other end a hollow extension 14 or other suitable means for receiving a hollow carrying member 15, which in turn is connected to a feeding needle 16. My connecting member 10 has a well 17 intermediate the screw threads 12 and extension 14. This well 17 may be partitioned by a wall 18 into two sections 19 and 20. Preferably adjacent the side opposite that having the extension 14 I provide a boss 21, having an air passage way 22 leading into section 20. The air coming into this air passage way 22 circulates through the well 17 and furnishes sufficient air to break the vacuum in the bottle 11. However, the air coming in through this passage way 22 unless sterilized may carry germs or foreign bodies which will pass through the glucose into the veins or system of a patient. I, therefore, provide a tubing 23 adapted to meet and connect with passage way 22 of boss 21. The tubing 23, which is hollow and has an air passage way 24, is connected to another tubing 25 within a heating means 26. The tubing 25, which is preferably constructed of glass but which may be made of metal or any other suitable substances, has a mouth 27 extending from the heating means 26 and is in direct contact with the atmosphere. Air coming in mouth 27 of tubing 25 enters the heater 26 and flows forward in the heater 26 as tubing 25 becomes a plurality of coils 28. These coils 28 are adjacent heating means 29, such as an electric filament. The air is thus heated and sterilized and destroys all foreign bodies in suspension as it passes on to tubing 24, passage way 22 and well 17 to break the vacuum in container 55

11 and cause the glucose therein to pour down through well 17, carrying member 15 and feeding needle 16. The tubing 25 being heated by heating means 26 will act as a filter and will destroy dirt, 5 dust, foreign matter, bacteria and germs which are held in the air in suspension thus producing a completely sterilized air. The air that breaks the vacuum in the bottle 11 with this structure cannot pass on any germs or foreign bodies to 10 the veins or system of a patient.

The heating means 26 may be electrical or any other convenient means or agency. In Fig. 5 I show an alcohol or gas burner 30 being used with my invention. This heating means which 15 is the only available means in some remote rural sections shall be large enough to house the coils 28. The heater 26 shown in Fig. 1 comprises a body member 31, insulation 32, air space 33 and a peep hole 34 by which the user can look in and 20 determine the amount of heat within. The heater 26 is connected by suitable cord 35 to switch 36 and pilot lamp 37 which will indicate when the current is on and by cord 38 to plug 39 which fits into the source of electric supply.

25 It may be desirable to direct the flow of heated air from glass tubing 25 through a cooler 40 by means of a detachable tube 56 before allowing the air to pass into air passage way 24. For this purpose I provide an air cooler 40 having a body 30 41 and a carrying member 42 for the air. Within the body member 41 are a plurality of plates 43 to aid in the cooling. The carrying member 42 carries the air on its outward flow through detachable tube 57 to air passage way 24.

35 In my preferred structure I find it desirable to employ a container 11 having a pair of grooves 44 and 45 as shown in Fig. 6. In groove 44 a laboratory sterilization indicator 46 is placed in said groove 44 before the container 11 leaves the 40 laboratory. When the container 11 is completely sterilized it will register permanently on the indicator 46 at the time of this sterilization and prove that the container and contents were sterile and sealed as such at the time they left the laboratory. Later when the container 11 is to 45 be used in the hospital a temperature indicator 47 is provided for the groove 45 for the second heating. Upon putting the container 11 again in hot water or other heating means the indicator 50 47 will indicate that the proper temperature for use has been obtained. This provides a double certification both before and after use on the sterilization of the container 11.

As another refinement in my apparatus I enlarge 55 part of the tubing 23 to provide a well 48 to house a thermometer 49 which will register when the flow of air in passage way 24 is at the proper temperature.

When giving intravenous or subcutaneous injections it is often important that the glucose, 60 or the like, in the container 11 be maintained at a certain temperature. With my invention the inflow of heated sterile air will aid in the maintaining of the desired temperature of the glucose since the sterile air when it enters the container 65 11 to break the vacuum is still heated and passes on its heat to the glucose and performs the double function of being a sterilizer as well as supplying heat.

70 I prefer to have the glass tubing 25 detachable from the tubing 23 and the connecting member 10 so that the connecting member 10 and its parts may be sterilized before use by submersion in boiling water or the like. Such submersion 75 might injure the glass tubing 25 and heating

means 26 which by its own action of heat will sterilize itself.

Frequently in hospitals, glucose, or the like, for giving intravenous or subcutaneous injections is poured into a funnel 50 as shown in Fig. 2. The extension 51 of the funnel 50 is connected to a hollow carrying member 15, which in turn is connected to a feeding needle 16. It has been customary to place gauze or other air admitting substances over the mouth 52 of the funnel 50. 10 This gauze does not sterilize nor completely filter the air so that infinitesimal germs and foreign bodies may pass through the gauze into the glucose and then into the system of the patient.

I provide a cap 53 to be sealed to the mouth 52 15 of the funnel 50 by screw threads 54 and 55 or other convenient means. I provide the cap 53 with an opening 56 through which I may insert a tubing 23 having a passage way 24. This tubing 23 which shall be detachable shall have 20 connected to it the above described heating means 26 preferably of electricity. Other heating means or agencies, however, may be used. In this way air will enter the air passage way 24 of the tubing 23 and be heated by the heating means 26 and 25 pass in a sterilized condition into the cap 53 so that the sterilized air will pass into the funnel 50 and break the vacuum so that the glucose, or the like, may flow.

Another form now in use in hospitals for giving 30 intravenous or subcutaneous injections comprises taking a sealed bottle 11 of glucose, or the like, as shown in Fig. 3 and puncturing the sealed cap so as to insert a hollow carrying member 15 which in turn is connected to a feeding needle 16. Another portion of the cap is punctured to supply air so as to break the vacuum in the bottle 11 through which opening a tubing 23 may be inserted. I connect this tubing 23, having an air 35 passage way 24, with a heating means 26. There 40 may be other forms to which I may add tubing 23 with air passage way 24 and heating means 26 so as to produce the same result as hereinbefore described.

In use my invention may be of service in giving 45 both intravenous and subcutaneous injections and is applicable when glucose, salt solution, serums or antitoxins are used. It may also be used for the injection of salvarsan. It is also possible to employ my invention for the irrigation of wounds. 50

My invention may also be applied to nonmedical and chemical as well as medical uses such as the pouring of distilled water or other fixed solutions or the transfer from one container to another where it is desired to keep the containers 55 and contents free from contamination and foreign bodies.

Having thus described my invention I claim:

1. A device for giving sterile injections comprising 60 a sealed container containing injection liquid, a removable connecting member attached to said container, a removable injecting member leading from said connecting member, said connecting member having a well and a passage way, a removable tubing connecting at one end with said passage way and leading to the atmosphere at its other end, and removable heating means connected to said tubing for superheating the air and destroying foreign bodies in the air passing 65 into said tubing, said air passing through the well in the connecting member and then into said sealed container to break the vacuum in said container and permit the injection liquid to flow 70 from said container through said well in the con- 75

necting member and thence into said injecting member.

2. A positive sterilizer in combination with apparatus for giving subcutaneous injections comprising a sealed fountain container containing injection liquid in inverted position, a connecting member removably attached at one end to said container, and having at its other end and to one side a hollow extension, a hollow carrying member 10 removably attached at one end to said hollow extension, a feeding needle removably attached to the other end of said hollow carrying member, said connecting member having a well intermediate its ends, said connecting member having 15 a boss at the side opposite said hollow extension, said boss having an air passage way leading from said well to a hollow tubing connected with said boss, an air intake tubing, an air-heating member, said air intake tubing passing through said air-heating member and connecting with the aforementioned hollow tubing leading to the air passage way within said boss, whereby said injection liquid may be passed direct to a patient without rehandling or exposure to contamination.
- 25 3. In combination with apparatus for giving subcutaneous and intravenous injections comprising a sealed fountain container containing injection liquid in inverted position and an injection needle, means for providing air positively

purified by both washing and heating to break the vacuum in the sealed container for permitting the liquid contained therein to flow comprising an air intake tubing, an air heating means, said air intake tubing passing through said air heating means wherein said air is superheated so that all foreign bodies in said air are destroyed, a connecting member removably attached at one end to said container, said connecting member having at its other end a hollow extension, a hollow 10 carrying member removably attached at one end to said hollow extension and at its other end to said injection needle, said connecting member having a well intermediate its ends, said connecting member having a boss at the side opposite 15 said hollow extension, said boss having an air passageway leading from said well, a hollow tubing connecting with said boss and with said air intake tubing for air after it has passed through said air heating means, said heated air 20 passing through said last mentioned hollow tubing into said well where it is again purified by washing in the liquid contained in said well, said doubly purified air then passing into said container to break the vacuum therein so that the 25 injection liquid may be passed directly to the patient doubly purified and without rehandling or exposure to contamination.

MARTIN C. SCHWAB.
